UNITED STATES PATENT OFFICE.

BENJAMIN A. MITCHELL, OF ST. GEORGE, NEW YORK, ASSIGNOR OF TWO-THIRDS TO
MINNIE L. MITCHELL, OF MAGNA, UTAH.

VIBRATING SCREEN.

Application filed October 16, 1918, Serial No. 258,466. Renewed May 17, 1923.

To all whom it may concern:

Be it known that I, BENJAMIN A. MITCHELL, a citizen of the United States, residing at St. George, Staten Island, in the county of Richmond and State of New York, have invented certain new and useful Improvements in Vibrating Screens, of which the following is a specification.

This invention relates to vibrating screens and more particularly to screens actuated for sifting ore, sand, gravel and the like.

This invention has for its general object an improved construction and arrangement of parts which is durable, efficient, and readily manufactured.

A more specific object of this invention is to provide improved apparatus of this character for carrying out screening processes without clogging.

Another object is to provide an arrangement in which the screen for the material to be screened is actuated by a vibrator utilizing the principle of rotating moments.

Another object is to provide improved means for applying to screens under tension, a harmonic motion of constantly changing direction.

Another object is to provide means for setting up vibrations of uniform amplitude throughout the width of screens.

Another object is to provide means for imparting vibrations in different phases to different parts of a screen.

Still another object is to provide improved means for connecting vibrators in operative relation with the screen to be actuated.

Other objects and advantages will in part be specifically pointed out hereinafter and in part obvious from the arrangements and constructions here set forth.

The invention accordingly consists in the features of construction, combinations of elements and arrangement of parts which will be exemplified in the construction hereinafter set forth, and the scope of their application will appear in the appended claims.

For a more complete understanding of the nature and advantages of this invention reference should be had to the following detailed description, which describes the best illustrative embodiments of this invention at present known to me, taken in connection with the accompanying drawing in which:

Fig. 1 shows a front elevation of screening apparatus embodying the improvements of my invention;

Fig. 2 shows a vertical sectional view taken on the line 2—2 of Fig. 1, looking in the direction of the arrows;

Fig. 3 shows an enlarged view of the vibrator and the means for connecting the same to the screen, part of the vibrator being shown in longitudinal section;

Fig. 4 shows an enlarged end view of the vibrator, illustrating the means for transmitting vibrations from the vibrator to the screen;

Fig. 5 shows an enlarged sectional view of the means for holding the opposite edges of the screen;

Fig. 6 shows an enlarged central vertical sectional view through the vibrator taken on the line 6—6 of Fig. 3;

Fig. 7 shows a vertical sectional view similar to Fig. 2, illustrating a modified arrangement of the apparatus;

Fig. 8 shows a vertical sectional view through the vibrator illustrated in Fig. 7, and

Fig. 9 shows a longitudinal view of the vibrator illustrated in Fig. 7.

Referring now to the drawing, and to Figs. 1 and 2 in particular, 20 denotes a hopper or other device supported in operative relation with a screen 40 which is adapted to feed the material to be screened through an outlet 23 controlled by a gate 24 onto the upper part of the screening surface. The supporting structure for the hopper as shown comprises a frame composed of members 21 and 22, which in addition supports the screen-frame 30 holding the screen 40 the vibrating means or "vibrator" 46 for the screen 40 also being supported at one side of the plane of the screen by this structure. The pressure of the material within the hopper tends normally to open the gate 24, and the degree of opening of the gate is controlled by a bolt 26 which passes through one of the bars 25, and is engaged at its outer end by a winged-nut 27. The loose material falling through the outlet opening 23 passes onto the screen 40 which is held in a screen-frame 30 the latter being hinged along its upper edge at the points 31 on the supporting frame of the apparatus.

The screen-frame is shown as constructed of

angle bar members or other suitable parts, forming a rectangular structure. The lower edges of the screen-frame 30 are provided with lugs 32 which pivotally engage the adjusting bars 33 having a plurality of apertures 34 therein to be engaged by removable bolts 35 passing through suitable frame members 22. The bolts 35 may be caused to engage any desired aperture 34, so that the lower edge of the screen-frame can be raised or lowered to change the inclination of the screen, as desired. The material passing onto the screen is screened in the manner hereinafter described, so that the finely divided material passes downwardly into a chute or hopper 36, while the coarse material passing off the lower edge of the screen falls into another chute or hopper 37.

The screen 40 is mounted within the rectangular frame 30, as shown in Fig. 1, and the opposite ends of the screen cloth are secured to the frame by an adjustable device illustrated more particularly in Figs. 3 and 5. The edge of the screen cloth is wrapped around a circular rod 41 located within a longitudinally slotted tube 42 with the overlapping parts of the screen extending outwardly through the slot, as illustrated in Fig. 5, so that when the tubes 42 at opposite edges of the screen are pulled apart, the edges 42^a of the slots press the screen against the rods 41 and cause the same to be securely gripped. The tubes 42 are engaged by bolts 43 having arms 43^a which extend partially around the tubes 42, as shown in Fig. 3. These bolts pass through apertures in the walls of the screen frame 30 and are threadedly engaged by the adjusting members 44, so that the screen can be stretched tightly within the frame and maintained continuously under relatively great tension, substantially similar to a drum-head, throughout the screening operation. As the screening process is carried on, it may be desirable from time to time to tighten the screen or to adjust the tension thereof to secure the most desirable results with the particular material being screened, and it is found in practice that the desirable tension of the screen will depend also upon its weight and stiffness. With particularly heavy and rigid screens, it is found that it is merely necessary to support the screen firmly within the frame with sufficient rigidity to prevent any considerable downward bending thereof and to maintain the same in a substantially rigid inflexible condition similar to the condition of a flexible screen stretched to a drum-head tightness. If desired, suitable guards 45 may be mounted along the lateral edges of the screen to prevent the material from passing over these edges.

The screen 40, as indicated, is stationarily supported so as to be vibrated independently of the screen-frame 30; this being accom-

plished by the vibrator 46, which, as will be seen, has within it rotating eccentric mass centres and utilizes the principle of rotating moments to produce relatively minute vibratory movements of constrained amplitude 70 having a constantly changing direction as set forth in my copending application Serial No. 275,321. As illustrated the vibrator 46 comprises a central casing 47 having bolted thereto the two end casings 48, each of which is reinforced by the longitudinally extending ribs 49. The central housing has its base 47^a mounted on a supporting beam 50 which is secured to the middle part of the lower wall of the screen-frame 30 and extends inwardly therefrom over the screen. A shaft 51 passes through the central housing 50 and has keyed thereon a pulley 52 which is adapted to be engaged by a belt 53 extending to a motor or other driving means. If 85 desired, the housing 47 may be made the casing of a motor and the armature of the motor mounted directly on the shaft, as hereinafter described. The details of the construction here employed are more clearly 90 illustrated in Figs. 3 and 6. So shown it comprises complementary portions secured together to form the housing 48, each portion of which is the same so that one set only will therefore be described. Mounted within 95 each housing 48 is a bearing ring 54 having a hard metal collar 55 secured to the outer side thereof and adapted to coact with balls 56, which run in a raceway formed by the annular collar 57 secured within the housing 100 48. Each end of the shaft 51 is reduced in diameter, and the reduced portion is keyed in a suitable recess formed in an unbalanced rotary member 58 having a lateral projection 59 on one side thereof. The lack of balance of this rotary member is further increased by providing an eccentrically located aperture 60 therethrough opposite the projection 59. Hard metal bearing collars 61 are secured to the ends of this unbalanced member, and these collars coact with ball-bearings 62 running in raceways formed by the collars 63 which are secured within the casing. The end thrust of the shaft and rotary members is taken up by hard metal plates 64 secured in the ends of the rotary members 58 and provided with central projections adapted to bear against the rounded surfaces of the hard metal caps 64, which are secured to the end walls 48^a of the housing. The space within each end housing 48 is filled with oil, or other lubricant, which is introduced through apertures closed by the plugs 65. The rotation of the shaft 51 at high speed produces high frequency vibrations in the casing due to the rotation of the unbalanced members 58.

The vibrations set up by the vibrator are imparted to the screen 40 by means of transmitting plates or members 68 which are car- 130

ried by the collars 69. The ends of the parts 48 of the vibrating casing are tapered, as illustrated in the drawings, and these portions are adapted to be closely fitted by the correspondingly tapered walls of the rings 69. Apertures are provided through the opposite walls of the casing to be engaged by the transverse keys 70 by which the rings 69 are securely clamped in position. The 10 rings 69 are rigidly secured to the transmitting members 68 by means of rivets or the like 71, and these transmitting members are in the form of relatively long plates, as illustrated in Figs. 1, 2, and 4, extending substantially across the screen in a direction transverse to the axis of rotation of the unbalanced rotary members. The lower edges of the transmitting members comprise longitudinally extending blocks or strips 72 of 20 wood, or other equivalent material, which strips bear directly upon the upper surface of the screen, as illustrated more particularly in Fig. 3, but which strips are not secured to the screen. The parts are so proportioned that the strips 72 bear rigidly against the screen surface, however, when the latter is in a rigid or substantially inflexible condition, as when a flexible screen is stretched to a substantially drum-head 30 tightness, so that the vibrations set up in the casing of the vibrator are imparted directly to the screen. The screen thus vibrates a high frequency independently of the frame in which it is mounted, and produces a thorough screening of the material which passes downwardly thereover.

Instead of employing the arrangement illustrated in Figs. 1 to 6, inclusive, it may be desirable in some instances to use the arrangement of apparatus illustrated in Figs. 7 to 9, inclusive, wherein the vibrator and its directly connected parts are mounted beneath the surface of the screen, thus leaving the space above the screen entirely free and unobstructed. In this modification, a supporting frame, comprising the vertically extending members 75 and the horizontal members 76, carries a hopper 78 from which the material is fed by a gate 79 onto an inclined 50 screen 80 mounted in the screen frame 81, which is hinged at the points 82 and supported at its lower end by means of adjustable rods 83 secured by the removable bolts 84, so that the inclination of the screen may be adjusted as in the embodiment of the invention previously described. The screen of this embodiment of the invention is capable of being stretched to and maintained under an extremely high degree of tension by 55 means of the adjustable device heretofore described. In this embodiment, however, the vibrator 85 has a central housing 86 which forms a casing of an electric motor, and the base 86^a of this motor is secured to a supporting beam 87 which is secured to the lower

part of the screen frame and extends upwardly beneath the middle portion of the screen, as shown in Fig. 7. In this embodiment, the shaft 51^a of the vibrator has the armature 88 of the motor secured directly thereto, so that the vibrator is driven directly by the motor, and the speed thereof may be varied as desired. The end casings 89 of this vibrator are similar to the casings of the vibrator previously described, and the clamping rings 90 mounted on the ends thereof are transmitted to clamping members 91 which extend upwardly and bear against the underside of the screen by means of the intermediate strips 92 of wood, or the like. This arrangement of the apparatus is similar to that previously described, in that the central housing is mounted on a part which is rigid with the screen frame, while the projecting and vibrating ends of the casing are operatively connected directly to the screen. The central housing in the last described embodiment is entirely closed, however, to prevent the access of dust to the interior of the vibrator, and this construction 90 has the advantage that the screen bears downwardly upon the transmitting members, so that the weight of the material on the screen tends to increase the contact between the screen and the transmitting members, whereas, in the first form of the invention described, the weight of the material tends to separate the transmitting members from the screen. The second invention has the further feature that it leaves the upper 100 surface of the screen entirely unobstructed. If desired, the vibrator of the second form of the invention may be further enclosed by a supplementary sheet metal housing 93.

With each form of the invention it is 105 found that improved results are obtained in the screening of crushed ore and other materials, due to the novel combination of the vibrating means and the screen. Due to the action of the rotary vibrator, which is 110 in direct connection with the screening medium, each and every particle of the screen vibrates in an extremely small circle, so that a vibration is set up in the screen which is in some respects the combination 115 of a vibration transversely of the screen and a vibration in the plane of the screen. This serves to sift the materials over the screen surface as they pass downwardly thereover by gravity, and to effect a more perfect 120 screening action than is possible with any form of screening device heretofore known. By the use of my improved vibrator it is possible to produce two series of vibrations in the screen through the two transmitting plates which are connected to opposite ends of the vibrator casing. The unbalanced 125 rotary members in opposite ends of the vibrator casing are preferably mounted 180° apart on the shaft, so that the vibrations 130

- produced thereby are opposite in phase, whereby the screening action is greatly improved. The primary and secondary vibrations produced directly in the screen by the 5 operation of the rotary vibrator are superimposed upon each other, so that with a rotation at the rate of 3600 revolutions per minute it is believed to be easily possible to obtain in the screen vibrations of about 18-, 10 000 or 20,000 per minute. This high frequency of the vibrations produced directly in the screen makes it impossible for materials to become clogged in the meshes of the screen, and thus the invention overcomes 15 the difficulty which has been present in all prior screen devices of which applicant is aware. Even when the powdered ore, or other material, is wet, it is found that the high frequency vibrations in the screen prevent 20 the material from adhering to the meshes of the screen and, at the same time, the materials fed to the screen pass therethrough at a more rapid rate than is possible with the ordinary screening devices. The 25 unbalanced rotary vibrator has the advantage that it produces a high frequency vibration without embodying cumbersome or complicated apparatus, and the frequency of vibrations may be readily varied by varying 30 the speed of rotation. The frequency of the vibrations in the screen may also be regulated by adjusting the tension of the screen, and although the desirable degree of tightness of the screen may vary under different 35 circumstances, it is preferred to stretch it to an extremely tight condition, approximating the tightness of a drum-head. In order to secure the best results with any given feed of material, it is desirable to adjust the tension of the screen according to the rate of 40 rotation of the vibrator and to the rate of feed of the material. With extremely heavy screens rigidly mounted in the frame, the vibrations produced are similar to those obtained with a lighter screen stretched to and 45 maintained under extremely high tension.
- Although I have shown and described certain embodiments of the invention for purposes of illustration, it will be understood 50 that it may be constructed in various different forms without departing from the scope of the appended claims.
- What I claim is:
1. In apparatus of the class described, an 55 inclined screen supported in substantially fixed position, and means for producing in said screen a plurality of simultaneously acting series of minute circular vibrations in planes perpendicular to the plane of the screen.
  2. In apparatus of the class described, an 60 inclined screen, and means for producing a plurality of series of minute circular vibrations directly in said screen in planes perpendicular to the plane of the screen, said
  3. In apparatus of the class described, an inclined screen, a vibrator casing, means for producing minute circular vibrations in said casing, and means for transmitting a plurality of simultaneously acting series of said vibrations to said screen throughout the width of the screen. 75
  4. In apparatus of the class described, a screen, means for holding said screen in a stiff rigid condition, a vibrator casing located outwardly from the plane of said screen, means for producing minute circular vibrations in said casing, and a rigid transmitting plate carried by said vibrator and contacting edgewise with said screen. 80
  5. In apparatus of the class described, a screen, means for holding said screen in a stiff rigid condition, a vibrator casing located outwardly from the plane of said screen, means for producing minute circular vibrations in said casing, and a pair of transmitting plates connected to the ends of 90 said casing and bearing edgewise on said screen throughout its width. 95
  6. In apparatus of the class described, a screen, means for holding said screen and maintaining the same under a tight drum-head tension, and means for producing a plurality of series of continuous vibrations of uniform amplitude across said screen in a plane at right angles thereto, the vibrations of each series being out of phase with 100 those of the other series. 105
  7. In apparatus of the class described, a rectangular screen frame, a rectangular screen, means for connecting opposite edges of said screen to said frame, adjustable means for producing tension in said screen, and means for producing a series of continuous circular vibrations in said screen in a plane perpendicular to the plane of the screen independently of said frame. 110
  8. In apparatus of the class described, a frame, a screen mounted in said frame, a supporting member projecting from said frame substantially parallel to said screen, and a rotating vibrator movably carried by 115 said supporting member arranged and connected to the intermediate portion of said screen for transmitting thereto harmonic motions executed in a plane transverse to the plane of said screen. 120
  9. In apparatus of the class described, a screen stationarily supported in screening position, a vibrator having a pair of rotating eccentric mass centres disposed in different phases, a support for said vibrator disposed between said centres, and means on said vibrator for imparting vibrations to said screen. 125
  10. In apparatus of the class described, a screen stationarily supported in screening 130

position, a vibrator actuated internally by a rotating moment for producing relatively minute vibrations executing a closed orbit, a support for said vibrator at one side of the plane of the screen, and means for imparting said vibrations to a plurality of portions of said screen.

11. In apparatus of the class described, a screen frame, a screen mounted in said frame, a rotary vibrator mounted on a fixed support opposite said screen, means for operating said vibrator, and rigid means connecting said vibrator with said screen for transmitting circular vibrations to said screen.

12. In apparatus of the class described, a screen frame, a screen mounted in said frame, a rotary vibrator mounted on a fixed support at one side of the plane of said screen, means for operating said vibrator, rigid means connecting said vibrator with said screen, and means for producing and maintaining tension in said screen.

13. In apparatus of the class described, a frame a screen mounted in said frame in a substantially rigid inflexible condition, a rotary vibrator carried by said frame between the edges of said screen and having a double oscillatory motion with respect to its support, and rigid means connecting the end portions of said vibrator with said screening medium.

14. In apparatus of the class described, a screen, a supporting member at one side of the plane of said screen, a rotating vibrator having a double vibratory movement about its centrally fixed support on said supporting member, a rigid plate connected to said vibrator and having one edge bearing against said screen, and means for operating said vibrator.

15. In apparatus of the class described, a screen frame, a screen detachably mounted on said frame, a rotating vibrator having a double oscillation about its central support mounted opposite the middle part of said screen, and transmitting means detachably mounted on said vibrator and bearing against said screen and transmitting to said screen circular vibrations in a plane perpendicular to said screen.

16. In apparatus of the class described, an inclined screen, means for feeding loose materials to the upper part of said screen, means for producing tension in said screen, a rotating vibrator mounted independently of said screen, and means for transmitting two series of uniform circular vibrations forming a continuous operative connection between said vibrator and said screen and perpendicular to said screen.

17. In apparatus of the class described, a screen, a vibrator casing mounted opposite said screen, said casing having two tubular parts, a ring secured on each of said tubular

parts, and plates carried by said rings and bearing on said screen perpendicularly.

18. In apparatus of the class described, a screen, a rotating vibrator having a double oscillating motion about its central support mounted opposite the central part of said screen, plates attached to the ends of said vibrator and bearing on said screen perpendicularly, and means for operating said vibrator.

19. In apparatus of the class described, a screen stationarily supported in screening position, a vibrator having a pivoted central portion and end portions adapted to execute vibrations of constrained amplitude and constantly changing directions in phases displaced by 180 degrees, rigid means on said end portions for transmitting said vibrations to said screen, and means for introducing material to be screened upon its upper surface.

20. In apparatus of the class described, a screen, a rotary vibrator comprising an electric motor having unbalanced rotary members on each end of its shaft one hundred and eighty degrees apart, and rigid members transmitting the characteristic vibrations of said vibrator to said screen in a plane perpendicular to the plane of said screen.

21. In an apparatus of the class described, a screen, means for stationarily supporting said screen in an inclined position, means for producing minute circular vibrations in the body of said screen, and means for passing loose materials to the upper part of said screen.

22. In an apparatus of the class described, a screen, means for maintaining said screen in a substantially stiff inflexible condition, means for supporting said screen in an inclined position, means for introducing loose materials onto the upper part of said screens, and means for producing true high frequency vibrations of minute circular motion directly in said screen and in a plane perpendicular to the plane of said screen.

23. In apparatus of the class described, a screen, means for maintaining said screen in a stiff rigid condition, means for supporting said screen in an inclined position, means for introducing loose materials onto the upper part of said screen, and means located opposite the plane of said screen and having a connection therewith for producing minute circular vibrations of high frequency directly in said screen and perpendicular to its plane of support.

24. The combination in a screening machine, of a rotary vibrator, means for supporting said vibrator at its center, transmitting plates connected to the free end portions of said vibrator, and a screen cloth extending over and vibrated by said transmitting plates.

25. The combination in a screening machine, of a vibrator casing, means for supporting said vibrator casing at its center leaving the end portions thereof free to vibrate, means for producing minute circular vibrations of high frequency in the end portions of said casing, transmitting plates connected to the end portions of said casing, and a screen cloth extending over and vibrated by said transmitting plates.
26. The combination in a screening machine of a vibrator casing, means for supporting said vibrator casing at its center

leaving the end portions thereof free to vibrate, means for producing minute circular vibrations of high frequency in the end portions of said casing, transmitting plates connected to the end portions of said casing, a screen cloth extending over said transmitting plates, and means for retaining said screen cloth on said plates and producing tension therein.

In testimony whereof, I have subscribed my name.

BENJAMIN A. MITCHELL.
